INDEX DEVICE

Stanley B. Freiberg, Cincinnati, Ohio, assignor to
The International Visible Systems Corporation,
Cincinnati, Ohio, a corporation of Ohio

Application December 17, 1930

Serial No. 502,963

10 Claims. (Cl. 16—128)

This invention relates to hinge structures.

The invention disclosed herein is especially adapted to use with hingedly mounted members, one or both of which comprise molded substances such as are made from condensation products made from formaldehyde and phenol.

An object of the invention is to provide a simple and substantial hinge structure that may be readily adapted to record books and the like, for example, as shown in my copending application Serial Number 385,884 filed August 14, 1929.

Another object of the invention is to provide a hinge structure of the character indicated, the parts of which may be readily assembled and disassembled, and the adjacent parts of which may be of corresponding or different construction one from the other, without interfering with proper functioning of the hinge members.

These and other objects are attained by the means described herein and disclosed in the accompanying drawing, in which:

Fig. 1 is a plan view of an illustrative model embodying the invention.

Fig. 2 is an enlarged sectional view on line 2—2 of Fig. 1.

Fig. 3 illustrates the component parts of a hinge structure embodying the invention.

The illustrations in Figs. 1 and 2 are illustrations merely of two hingedly connected members, one or both of which may have formed upon it, hinge structures embodying the invention. It is to be understood that either one of hinged elements such as 10 and 11 may carry a suitable pintle or hinge pin 12 and that one only of the carrier or mounting members such as 10 and 11, may carry elements conforming with the invention.

In Fig. 2 the hinge member or cover 10, preferably of molded material which may comprise laminated fabric and condensation products of formaldehyde or phenol, is provided with a yoke-like extremity, the arms 13 and 14 of which are spaced by a recess 15. Within the recess 15 there is disposed a pintle or hinge pin 12. The outer surfaces of the arms 13 and 14 are preferably arcuate and are enclosed within a clip 16. The clip is substantially of C shape and is preferably 50 of spring material. The throat 17 of the clip 16 is of such size that it will receive the reduced portion 18 of the cover 10 and which reduced portion 18 connects the arms 13 and 14 and the main portion or body of the cover member 10.

A key, plug or wedge 19 is introduced into the

clip 16 and extends between the arms 13 and 14 and the inner face of the clip 16 for closing the mouth of the recess or pocket 15 and thereby confining the pintle or hinge pin 12.

At intervals along the members 10 and 11 there are provided bifurcated lugs 20 comprising the indicated arms 13 and 14 and for each of such lugs there is provided a clip 16 and a wedge or key 19. The lugs 20 are so spaced that similar lugs formed on the member 11 may be received between adjacent lugs 20 on the member 10.

In assembling a pair of members 10 and 11, the various clips such as 16 and wedges 19, are assembled or associated with their respective cooperating lugs 20, formed on the members 10 and 11. Thereupon the lugs on the member 10 are interposed between the lugs on the member 11, and the hinge pin 12 may then be driven through the aligned recesses 15 in the various aligned lugs 20 formed upon the members 10 and 11.

It is to be understood that inasmuch as the hinge structure disclosed herein is intended primarily for attaching molded members to a hinge pin or pintle, it is not necessary that both hingedly connected members such as 10 and 11 shall comprise the specific hinge structure disclosed, it being sufficient that one of the members, for example, 11, be adapted to carry a pintle such as 12, on which the hinge members associated with a member such as 10 may be mounted. It is also to be understood that essentially the invention relates to a molded hinge structure, the particular members connected by such hinge structures being immaterial. It is to be understood that the hinge members are formed from a plastic substance and that upon curing of such substance by heat and/or pressure or by any other agencies or means, the hinge members are given stability and rigidity.

In view of the fact it has been sought, without success, to mold hinge structures with pintle receiving pockets or openings, and whereas the invention disclosed herein is directed to the art of hinge members molded from substances that attain rigidity incident to the molding thereof, the invention is not restricted to the specific substances mentioned herein, but comprehends molded hinge members of various plastic, powder and other forms of substances that may be molded and/or cured for providing a rigid product that may serve as a hinge member or the like.

What is claimed is:

1. A hinge comprising a pin, a bifurcated lug

110

receiving the pin between the arms of the lug, a member extending between the arms of the lug, and a clip extending about the arms of the lug and the said member for retaining said member and arms in relatively fixed positions.

5. 2. A hinge structure comprising a hinge pin, a member on which the hinge pin is mounted, a second member having a bifurcated portion receiving the hinge pin between the arms of said bifurcated portion, a plug extending between the arms of said bifurcated portion for confining the hinge pin between said plug and said arms, and a clip for holding the plug and arms in fixed relationship.

10. 3. The combination of a molded hinge lug having divergent arms and a seat formed between the arms, a hinge pin on said seat, a clip enclosing the arms, a key between the clip and the hinge lug for retaining the pin on the seat and a mounting for the hinge pin.

15. 4. In a hinge the combination of a pair of molded carrier members each having integral molded lugs, the lugs being staggered whereby recesses are provided between adjacent lugs on 25 the same carrier members and into which recesses, the lugs on the other carrier member extend, each lug comprising divergent arms and a seat formed between the arms, a clip for each lug and enclosing the arms of their respective lugs, a 30 hinge pin extending along all of the lugs and received by all of the seats on said lugs, and a key for each lug and extending between the arms of its respective lug and its respective clip for retaining the hinge pin on the seat of its respective lug.

35. 5. A hinge structure comprising a hinge lug having a seat formed thereon and having an outwardly exposed clip receiving surface, a hinge pin received on the seat and a clip mounted upon 40 the clip receiving surface of the lug, said clip substantially enclosing the lug and restraining the hinge pin from movement radially relative to the hinge lug.

45. 6. The combination of a carrier member, a hinge lug integral with the carrier, the lug having

an open seat formed thereon and opening away from the carrier member, a hinge pin on the seat and means including a clip for closing the seat, retaining the hinge pin on the seat and having its ends disposed on opposite sides of the lug and at the junction of the lug and the carrier member.

50. 7. The combination of a carrier member, a hinge lug integral with the carrier and connected together by a reduced portion, said lug comprising spaced arms and an open seat between the arms, a hinge pin on the seat and means including a clip having a throat, closing the seat for retaining the hinge pin on the seat, the throat of the clip receiving the reduced portion at the junction of the carrier member and the lug.

55. 8. The combination of a carrier member, a hinge lug integral with the carrier, the lug having an open seat formed thereon and opening away from the carrier member, a hinge pin on the seat, a key closing the seat and confining the hinge pin to said seat, and a clip substantially enclosing the lug and holding the key in position.

60. 9. The combination of a carrier member, a hinge lug integral with the carrier and connected together by a reduced portion, said lug comprising spaced arms and an open seat between the arms, a hinge pin on the seat and means including a key and a clip having a throat, closing the seat for retaining the hinge pin on the seat, the throat of the clip receiving the reduced portion at the junction of the carrier member and the lug, the key extending between the free ends of the arms for confining the hinge pin to the seat and the clip restraining the key from separation from the arms.

65. 10. A hinge structure comprising a hinge lug having a seat formed thereon and having an arcuate outwardly exposed clip receiving surface, a hinge pin received on the seat and an arcuate clip mounted upon the arcuate clip receiving surface of the lug and restraining the hinge pin from movement radially relative to the hinge lug.
